CONTROL MECHANISM FOR PRESSES

Karl Friedrich Wagner, Stuttgart, Germany, assignor, by mesne assignments, to Magnesium Development Corporation, Newark, N. J., a corporation of Delaware

Application August 31, 1931, Serial No. 560,431
In Germany September 15, 1930

4 Claims. (Cl. 137—139)

This invention relates generally to control mechanisms and particularly to control mechanisms for automatically-operated hydraulic or pneumatic presses, such as die-casting machines and the like.

Control mechanisms for automatically-operated machines of the type above referred to usually comprise a shaft provided with a series of cams which actuate the valves for admitting and releasing the pressure to and from various parts of the machines to control their normal cycle of operations. It is often necessary, in the operation of automatic presses, to change from automatic to hand operation. This is particularly desirable when the working conditions attendant to a new object, or work-piece, are to be ascertained, or where only a small number of a particular object or work-piece are to be made.

In present cam-controlled presses the cams, which actuate the various valves in the operation of such mechanisms, are usually arranged on a single shaft, each cam serving to open a valve by means of a suitable tappet, whereas the closing of the valves is usually effected by means of springs. Valve mechanisms involving springs are not always reliable, and in the present invention the inherent disadvantages of such mechanisms have been eliminated.

The main object of the present invention is to provide an automatic control mechanism for hydraulic or pneumatic presses which is simple in construction and which may be readily changed over from automatic to hand or manual operation. Other objects will be apparent on consideration of the following description when taken in connection with the attached drawing in which:

Fig. 1 represents, in diagrammatic form, a front view of a valve control mechanism comprising a pair of cams mounted upon a pair of cam shafts and means for automatically operating said valves;

Fig. 2 represents a view similar to that shown in Fig. 1 in which the mechanism is adapted to be manually or hand operated;

Fig. 3 represents, in diagrammatic form, a section taken on the line III—III of Fig. 1;

Fig. 4 is a fragmentary view, to enlarged scale, in part section and with parts broken away illustrating the interconnection between the tappets c^1 and c^2 with the bell-crank lever d .

In order to insure the positive actuation of cam-operated valves in both directions, without unduly extending the length of the cam shaft, the valves in the present invention are arranged

in pairs, one valve in each pair serving to admit pressure and the other valve serving to release pressure. Positive actuation of the valves is provided for in the form of a bell-crank lever or the like to which the tappets of the respective valves in each pair are connected. Cams for actuating the valves in controlling the various operations of the machine are suitably mounted adjacent each other and in the same plane on two separate shafts and cooperate with the bell-crank lever to simultaneously open and close the valves in each pair. To insure proper cooperation of the cam shafts, and the correct relative positions of the cams mounted thereon, the two cam shafts are connected together by means of a suitable gear train or by cog-wheels.

Both of the cam shafts according to this invention are supported in such a manner that they may be moved apart or separated to a moderate extent to remove the cams from their cooperating positions with respect to the aforementioned bell-crank lever. When separated the cams are prevented from actuating the valves, which may then be manually or hand operated. Preferably the separation of the two cam shafts is limited to an extent which permits the gear train or cog-wheels to remain in loose mesh, which condition retains the accurate registry of the cams when the mechanism is returned to automatic control.

Referring particularly to the drawing a represents a single distributor, a number of which are usually combined to form a unit disposed in a direction parallel to the cam shafts. Each distributor comprises a pair of valves b^1 and b^2 , respectively, one of which, in its open position, admits pressure, whereas the other valve, in its open position, releases pressure. Each pair of valves is actuated by means of a bell-crank lever d composed of spaced plates (Fig. 3) provided with a free arm k , which bell crank is adapted to reciprocate the valve tappets c^1 and c^2 , respectively. The tappets c^1 and c^2 are each adjustably attached through a nut and threaded connection to block or link members l , which extend downwardly between the spaced plates of the bell-crank lever d , as shown in Fig. 4. A slot 3 in the members l and suitable pins 2, fixed in the spaced plates comprising the bell-crank lever d , provide a suitable connection permitting positive vertical reciprocation of tappets c^1 and c^2 , together with their valves b^1 and b^2 respectively. The valves b^1 and b^2 are preferably formed integral with the tappets c^1 and c^2 respectively. The free arm k of the bell-crank is

provided with a cam follower or roller f which, during automatic operation, is engaged by the oppositely-disposed cams n^1 and n^2 keyed to tubular shafts or sleeves m^1 and m^2 rotatably mounted upon the eccentric portions p^1 and p^2 of the parallel shafts r^1 and r^2 . The shafts r^1 and r^2 are suitably journaled and are adapted to be simultaneously rotated, in opposite directions, through the medium of gears or cog-wheels q^1 and q^2 , or handles x^1 and x^2 , fixed to the shafts r^1 and r^2 . This construction permits the eccentric portions p^1 and p^2 of the parallel shafts to be separated a moderate distance from the position shown in Fig. 1 to that shown in Fig. 2, in which latter position the cams are removed from engagement with the follower f and the valves may be operated manually.

Preferably formed integrally with the cams n^1 and n^2 are gears or cog-wheels g^1 and g^2 , which, as shown in Fig. 3, are not in the same plane but are offset with respect to each other and mesh with an idler pinion or cog-wheel s mounted upon the shaft t in any suitable manner. It will be readily understood that the gears g^1 , g^2 and s will remain in mesh whether the cams n^1 and n^2 are in contact with the cam follower f , as shown in Fig. 1, or removed therefrom, as shown in Fig. 2, the loose engagement of the gear teeth, in the position shown in Fig. 2, being sufficient to retain the cams in proper relative position with respect to each other. This arrangement of gears permits a means for driving the control mechanism, as it is possible to drive the shaft t in any suitable manner. Furthermore, the shaft t may be driven at any suitable predetermined speed in accordance with the desired speed of operation of the control system.

As shown in the drawing, the contour of the cams n^1 and n^2 is identical and the cams are provided with relatively large crests l^1 and l^2 and relatively small crests v^1 and v^2 . The crests v^1 and v^2 are brought into position in engagement with the follower f once during each revolution of the cams n^1 and n^2 , which rotate in the direction indicated by the arrows in Fig. 1. In the position shown in Fig. 1 the free arm k of the bell-crank lever d is brought into a vertical position and both of the valves b^1 and b^2 are closed. Continued rotation of the cams from the positions shown in Fig. 1 oscillates the bell-crank lever d whereby valve b^2 is opened or raised and valve b^1 remains closed during the first 180° of rotation, whereas during the second half of the cycle valve b^1 is opened and valve b^2 is closed. The crests v^1 and v^2 therefore insure a definite dwell during each complete revolution of the cams n^1 and n^2 , at which time both valves are in their closed position.

In order to change from automatic to manual or hand control it is only necessary to rotate the shafts r^1 and r^2 through 180° in any suitable manner by means of the handles x^1 and x^2 or the gears q^1 and q^2 , which action separates the cams n^1 and n^2 a definite distance, in view of their eccentric mounting, and permits manual control of the valves through the medium of the grip h attached to the bell-crank lever d .

I claim:

1. In a device for controlling the operation of automatic fluid-operated presses, a pressure distributor comprising a valve for admitting pressure and a valve for releasing pressure, oscillatory means for positively actuating said valves, a pair of shafts journaled a definite distance

apart, said shafts having eccentric portions formed thereon, a cam rotatably mounted on each of said eccentric portions, means for rotating said shafts to change the relative positions of said eccentric portions and to thereby separate said cams, and means associated with said cams for maintaining definite relationship therebetween for all positions thereof, said cams being adapted to impart an oscillatory movement to said valve-actuating means.

2. In a device for controlling the operation of automatic fluid-operated presses, a pressure distributor comprising a valve for admitting pressure and a valve for releasing pressure, oscillatory means for positively actuating said valves, a pair of parallel shafts journaled a definite distance apart, said shafts having eccentric portions formed thereon, a cam rotatably journaled on each of said eccentric portions, means for rotating said shafts to change the relative positions of said eccentric portions and to thereby separate said cams, and gears associated with said cams for driving the same at predetermined equal speed and for maintaining definite relationship therebetween for all positions thereof, said cams being adapted to impart an oscillatory movement to said valve-actuating means on rotation of said cams.

3. In a device for controlling the operation of automatic fluid-operated presses, a pressure distributor comprising a valve for admitting pressure and a valve for releasing pressure, a bell-crank lever connected to valve tappets associated with said valves, a pair of parallel shafts journaled a definite distance apart, said shafts having eccentric portions formed thereon, a cam rotatably journaled on each of said eccentric portions, means associated with said shafts for rotating the same to change the relative positions of said eccentric portions and to thereby separate said cams, and means mounted on said eccentric portions in association with said cams for driving the same at predetermined equal speed, said last-mentioned means being adapted to maintain definite relationship between said cams for all positions thereof, said cams being adapted, on rotation, to impart an oscillatory movement to said bell-crank lever.

4. In a device for controlling the operation of automatic fluid-operated presses, a pressure distributor comprising a valve for admitting pressure and a valve for releasing pressure, a pair of parallel shafts journaled a definite distance apart, said shafts having eccentric portions formed thereon, a tubular shaft rotatably mounted on each of said eccentric portions and having a cam secured to each tubular shaft, a bell-crank lever pivotally mounted and having a depending free arm disposed between and adapted to cooperate with said cams, means associated with said shafts for rotating the same to change the relative positions of the eccentric portions and to thereby separate said cams and remove the same from cooperating position with respect to said bell-crank lever, tappets associated with said valves and bell-crank lever, and means for driving said tubular shafts at a predetermined equal speed whereby said bell-crank lever is oscillated and said oscillatory movement is imparted to said tappets to positively actuate said valves, said cams in their separated position permitting actuation of the valves through manual operation of said bell-crank lever.

KARL FRIEDRICH WAGNER.
